United States Patent Office

Des. 189,269
Patented Nov. 15, 1960

189,269

COMBINED CAMERA AND FLASH UNIT

George Irwin, Chicago, Ill., assignor to Herbert George Company, Chicago, Ill., a corporation of Illinois

Filed Feb. 27, 1958, Ser. No. 49,816

Term of patent 14 years

(Cl. D61—1)

FIG. 2

FIG. 1

FIG. 3

FIG. 4

FIG. 5

FIG. 6

FIG. 7

FIG. 8

FIG. 9

Figure 1 is a front elevational view in closed position of a combined camera and flash unit showing my new design;

Figure 2 is a left side elevational view thereof;

Figure 3 is a right side elevational view thereof;

Figure 4 is a rear elevational view thereof;

Figure 5 is a front elevational view thereof in open position;

Figure 6 is a top plan view thereof in open position;

Figure 7 is a bottom plan view thereof;

Figure 8 is a perspective view thereof; and

Figure 9 is a perspective rear view thereof.

I claim:

The ornamental design for a combined camera and flash unit, as shown.
